UNITED STATES PATENT OFFICE.

HANS A. LARSEN, OF MINNEAPOLIS, MINNESOTA.

WRENCH.

SPECIFICATION forming part of Letters Patent No. 334,077, dated January 12, 1886.

Application filed September 15, 1884. Serial No. 143,091. (No model.)

To all whom it may concern:

- Be it known that I, HANS A. LARSEN, a citizen of the United States, residing at Minneapolis, in the county of Hennepin and State 5 of Minnesota, have invented a new and useful Improvement in Wrenches; and I hereby declare that the following is a full, clear, and exact description of the same, reference being had to the accompanying drawings.
- 10 My invention relates to the class of wrenches known as "monkey-wrenches;" and the object of the invention is to provide means whereby the movable jaw can be more quickly adjusted than by the screw commonly used.
- 15 My invention consists in providing a spring at the back of the wrench under the sleeve which bears the movable jaw, by means of which spring a serrated section of the lower portion of the sleeve is held in engagement 20 with a serrated bar provided on the lower edge of the shank; and in providing a thumb-piece and guard to facilitate the use of the spring, and in certain details of construction hereinafter more fully set forth.
- 25 In the drawings, Figure 1 is a side elevation of the wrench; Fig. 2, a vertical longitudinal view of the same, and Fig. 3 a top view.
- A is the shank bearing the fixed jaw.
- 30 a a' is the movable jaw carried by the sleeve B. The sleeve B fits loosely about the shank A. The movable jaw a' is rounded interiorly in its upper portion for the purpose of pivoting the jaw and sleeve at that point to allow 35 the rear end of the sleeve to be moved up and down, and the lower portion of the jaw a' fits closely to the shank A, and a recess, d, is provided at the middle to permit the jaw to slide over the bar e, hereinafter described.
- 40 e³ are serrations provided at the inside of the lower portion of the sleeve B. I preferably use for the purpose a short steel bar, as e', secured in the lower part of the sleeve.
- e is a steel bar having serrations e², and is cast 45 in or otherwise suitably secured to the lower edge of the shank A, and should extend from near the handle to the forward end of the shank and within the jaw a, to prevent dis-

placement. The serrations of this bar fit into those provided in the sleeve and hold the 50 sleeve and movable jaw in place.

c is a semi-elliptic spring interposed between the upper portion of the sleeve and the back of the shank and riveted to the sleeve. Both ends of the spring are free to slide along 55 the back of the shank when the sleeve is shifted. The spring lifts the rear end of the sleeve and holds the serrations e³ and e² in engagement, preventing the slipping of the movable jaw when the wrench is being operated. 60

f is an extended thumb piece at the back of the sleeve, affording a leverage for operating the spring c.

b is a guard, preferably cast as a part of the ferrule h, and fitted into a notch in the under 65 edge of the shank A, and should extend about two or two and a half inches along the shank. It should be just sufficiently removed from the shank to permit the sleeve to pass under it. The guard enables the tool to be more firmly 70 gripped in depressing the spring c and adjusting the jaws, and keeps the fingers from contact with the bar e, where they are liable to be pinched in shifting the sleeve.

When it is desired to adjust the jaws, the 75 tool should be grasped about the guard b, with the thumb resting on the part f. Then, by pressure of the thumb, the sleeve and jaw a' are rendered free to be quickly adjusted to the desired position. 80

Having fully described my invention, what I desire to claim and secure by Letters Patent is—

The combination, with the shank A, bearing the fixed jaw a, and provided with serrations e², 85 of the sleeve B, carrying the jaw a', which is rounded interiorly in its upper portion to pivot said jaw and sleeve on the shank A, the serrations e³ in the lower portion of said sleeve, the spring c, secured beneath the thumb-piece 90 f, and the guard b, all constructed and arranged substantially as described.

HANS A. LARSEN.
